(57) **CLAIM**

The ornamental design for an earhook for earpieces, as shown and described.

DESCRIPTION

FIG. 1 is a front perspective view of an earhook for earpieces;

FIG. 2 is a rear perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a front perspective view of an earhook for earpieces assembled to an earpiece;

FIG. 10 is a front perspective view of an earhook fr earpieces separated from the earpiece;

FIG. 11 is a rear perspective view of an earhook for earpieces assembled to an earpiece; and,

FIG. 12 is a rear perspective view of an earhook for earpieces separated from the earpiece.

The broken line showing of the environment is for illustrative purposes only and forms no part of the claimed design.
